UNITED STATES PATENT OFFICE.

CHARLES DAVID BONSALL AND PAUL E. FINGER, OF PITTSBURGH, PENNSYLVANIA,
ASSIGNORS TO P. H. MURPHY COMPANY, OF NEW KENSINGTON, PENNSYLVANIA,
A CORPORATION OF PENNSYLVANIA.

CAR ROOF.

Application filed March 2, 1928. Serial No. 258,508.

This invention relates principally to metal car roofs of the flexible single course type wherein the carlines are connected to the side plates by brackets and the roof sheets 5 are arranged between the carlines with their adjacent side margins loosely connected by seam covers, which rest on said carlines, and with their eaves ends supported on wooden fascia members that are bolted to the vertical faces of said side plates.

One of the principal objects of the present invention is to utilize the carline brackets as a means for supporting the eaves ends of the roof sheets. Another object is to utilize 15 the carline bracket as a support for a loading-lifting attachment. Other objects are simplicity and cheapness of construction and compactness of design.

The invention consists in the carline 20 bracket and in the construction, combinations and arrangements of parts hereinafter described and claimed.

In the accompanying drawing, which forms part of this specification and wherein 25 like symbols refer to like parts wherever they occur,

Fig. 1 is a plan view of a portion of a car roof embodying my invention;

Fig. 2 is an enlarged vertical cross-section 30 through the eaves portion of the car on the line 2—2 in Fig. 1;

Fig. 3 is an enlarged fragmentary plan view of the eaves portion of the car roof; and

Fig. 4 is a vertical cross-section through the seam, carline and carline bracket on the line 4—4 in Fig. 2.

Referring to the accompanying drawing, our invention is shown in connection with a 40 car roof comprising Z-bar side plates 1 arranged with their webs horizontal and with one flange in and extending upwardly. The Z-bar side plates on opposite sides of the car are connected by metal carlines 2 preferably 45 of substantially inverted channel-shape provided with outstanding base flanges 3 at the lower edges of their side walls.

Metal roof sheets 4 extend from side to side of the car between carlines and rest on purlins 5 secured to the carlines and preferably also have their eaves end portions supported on wooden fascia strips 6 that are 50 removably secured flatwise to the outer or

vertical face of the upstanding inner flanges of the side plates preferably by means of 55 bolts 7. The roof sheets are narrower than the spaces between the channel portions of the carlines and are provided with depending eaves flanges 8 that overhang the outer edges of the wooden fascia members 6 and 60 terminate at their lower ends in inturned flanges that are spaced away from said fascia members, whereby said sheets are independently movable.

The roof sheets are provided along their 65 adjacent side margins with upstanding flanges 9 that are loosely connected by seam covers 10 of substantially inverted channel-shaped section that have lateral base flanges 11 that bear against the body portions of 70 the sheets inside the side marginal flanges thereof. The seam covers rest on and are riveted to the flat tops of the carlines and are provided at their eaves ends with depending flanges 12 that overhang and are 75 spaced from the eaves corners of adjacent sheets and terminate at their lower ends in inturned flanges which extend beneath and are spaced below the inturned lower ends of the depending eaves flanges adjacent to the 80 roof sheets.

As shown in the drawing, each end of a carline 2 is rigidly secured to an adjacent side plate 1 by means of an angle-shaped carline bracket A. The carline bracket is 85 disposed beneath the end of the carline with its vertical flange 13 down and riveted flatwise to the outer face of the upstanding inner flange of the Z-bar side plate and with its other flange 14 extending inwardly beneath the end of the carline and riveted flatwise to the outstanding base flanges 3 thereof. The inwardly extending carline supporting flange 14 of the carline bracket A is made wider than the carline and has its 90 side marginal portions offset upwardly, as at 15, on opposite sides of the carline to provide a channel-shaped seat for the end of the carline and outstanding flanges at the tops of the side walls of said channel for 100 supporting the side marginal portions of adjacent sheets near their eaves ends.

The web of the carline supporting channel in the inwardly extending flange 14 of the carline bracket A is also provided beneath the downwardly opening channel of 105

the carline with a downwardly bossed circular opening 16, through which the chains or ropes of a load lifting device (not shown) may be passed. As shown in the drawing, 5 the web of the carline supporting channel in the inwardly extending flange 14 of the carline bracket is provided at the end of said flange and opposite the bossed opening 16 with a depending stiffening flange 17, which 10 flange, together with the flange which surrounds said opening, is rounded off where it joins the supporting flange of the carline bracket to prevent chafing or wear of the chain or rope of the load lifting device.

15 By the arrangement described the sheets rest on the upwardly offset side marginal flange portions 15 of the carline bracket, whereby the eaves ends of the sheets are prevented from sagging and thus causing the 20 seams to leak at the eaves in the event that the wooden fascia gives way due to rotting of the fascia or loosening of its securing bolts. Another advantage of the present construction is that it dispenses with the use 25 of separate attachments for supporting the load lifting device and thus saves the cost of such attachments.

It is evident that the carline bracket hereinbefore described is applicable for use with 30 cars having side plates, carlines and seams of various construction; therefore, we do not wish to be limited to the details of construction shown and described.

What we claim is:

35 1. A car roof comprising side plates connected by carlines, roof sheets located between carlines and carline brackets secured to said side plates and to the undersides of said carlines, said carline brackets having upwardly offset side marginal portions extending on opposite sides of said carline beneath adjacent sheets and constituting supports therefor.

40 2. A car roof comprising side plates connected by carlines, roof sheets located between carlines and carline brackets secured to said side plates and to the undersides of said carlines, said carline brackets having upwardly offset side marginal flange 45 portions extending on opposite sides of said carline beneath adjacent sheets and constituting supports therefor, said carline brackets being provided with means for supporting load lifting devices.

50 3. A car roof comprising side plates connected by carlines, wooden fascia members secured to the vertical faces of said side plates, roof sheets extending from side plate to side plate between carlines with their 55 eaves ends supported on said fascia members, seam covers supported on said carlines and loosely connecting adjacent sheets, and carline brackets secured to said side plates and to the undersides of said carlines, said

brackets being made wider than the carlines and having the portions thereof located beyond the side of said carlines offset upwardly for supporting adjacent sheets on opposite sides of said carlines. 70

4. A car roof comprising side plates connected by carlines, wooden fascia members secured to the vertical faces of said side plates, roof sheets extending from side plate to side plate between carlines with their eaves ends supported on said fascia members, seam covers supported on said carlines and loosely connecting adjacent sheets, and carline brackets secured to said side plates and to the undersides of said carlines, said 75 brackets being provided with means for supporting adjacent sheets on opposite sides of said carlines, and means on said brackets beneath said carlines for supporting a load lifting device. 80

5. A car roof comprising side plates connected by carlines, wooden fascia members secured to the vertical faces of said side plates, roof sheets extending from side plate to side plate between carlines with their eaves ends supported on said fascia members, seam covers supported on said carlines and loosely connecting adjacent sheets, and carline brackets for securing the ends of said carlines to said side plates, each of said 90 carline brackets comprising a flange secured to the side plate and a flange extending beneath the end of the carline and rigidly secured to the underside thereof, the carline supporting flange of said bracket being provided with a channel-shaped seat for the carline and outstanding flanges at the top of the side walls of said channel for supporting the eaves corner portions of adjacent roof sheets. 95

6. A car roof comprising side plates connected by inverted channel-shaped carlines, wooden fascia members secured to the vertical faces of said side plates, roof sheets extending from side plate to side plate between carlines with their eaves ends supported on said fascia members, seam covers supported on said carlines and loosely connecting adjacent sheets, and carline brackets for securing the ends of said carlines to said side plates, each of said carline brackets comprising a flange secured to the side plate and a flange extending beneath the end of the carline and rigidly secured to the underside thereof, the carline supporting flange of said 110 bracket being made wider than the carline and having the side marginal portions thereof located beyond the sides of the carline and offset upwardly to constitute supports for adjacent roof sheets, said carline supporting flange having an opening located beneath the inverted channel of the carline 115 adapted to receive a load lifting device. 120

7. A carline bracket having a flange pro- 130

- vided with a channel-shaped carline seat and outstanding sheet supporting flanges at the inner edges of the side walls of the channel-shaped carline seat.
5. 8. A carline bracket having a carline supporting flange provided with upwardly offset side marginal flange portions adapted to support roof sheets.
9. A carline bracket having a flange provided with upwardly offset sheet supporting flange portions and means located between said flanges for attaching a load lifting device to said flange.
10. A carline bracket having a carline supporting portion and also having a roof sheet supporting portion.
11. A carline bracket having a carline supporting portion provided with a channel seat for a carline, the web of said channel seat being provided with means for supporting a load lifting device and the sides thereof being provided with outstanding flanges for supporting car roof sheets.
12. A carline bracket having a flange adapted to be secured to a side plate, and a flange adapted to support one end of a carline, said carline supporting flange being provided at its opposite sides with upwardly offset sheet supporting flange portions and having an opening therein adapted to receive a load lifting device.

Signed at New Kensington, Pa., this 27th day of Feb. 1928.

CHARLES DAVID BONSALL.
PAUL E. FINGER.
